PULSATING SCREEN

2 Sheets-Sheet 1

This technical drawing illustrates a multi-tiered shelving unit, specifically Fig. 1. The structure consists of several horizontal shelves supported by vertical legs. The shelves are made of a material with a hatched pattern. Numerous components are labeled with numbers:

- 6: Vertical leg on the right side.
- 9: Vertical leg on the bottom right.
- 11: Shelf on the bottom tier.
- 12: Shelves on the middle and top tiers.
- 18: Horizontal support bar on the middle tier.
- 19: Vertical support bar on the middle tier.
- 21: Vertical support bar on the top tier.
- 22: Horizontal support bar on the top tier.
- 24: Horizontal support bar on the middle tier.
- 25: Vertical support bar on the middle tier.
- 26: Vertical support bar on the top tier.
- 27: Vertical support bar on the top tier.
- 28: Vertical support bar on the middle tier.
- 29: Vertical support bar on the top tier.
- 30: Horizontal support bar on the top tier.
- 31: Horizontal support bar on the middle tier.
- 32: Horizontal support bar on the bottom tier.
- 33: Long horizontal bar on the top tier.
- 34: Long horizontal bar on the middle tier.
- 35: Long horizontal bar on the bottom tier.
- 36: Long horizontal bar on the top tier.

PULSATING SCREEN

Walter J. Hartwig, Wausau, Wis., assignor to D. J.
Murray Manufacturing Co., Wausau, Wis., a
corporation of Wisconsin

Application September 15, 1944, Serial No. 554,189

2 Claims. (Cl. 92—32)

1

The present invention relates generally to improvements in the art of screening, and relates more specifically to improvements in the construction and operation of diaphragm actuated flat screens for fibrous pulp or the like.

The primary object of my invention is to provide various improvements in the details of construction of diaphragm actuated flat screen assemblies, whereby the construction is simplified, the manufacture thereof is expedited, and the efficiency is enhanced to a maximum.

It has long been common practice in the paper making industry, to utilize diaphragm actuated flat screens for the purpose of treating fibrous pulp, and these screens are ordinarily arranged in groups within elongated vats. The individual screen decks or plates of these screen assemblies must frequently be removed from their normal moorings either for cleaning and renewal, or in order to gain access to the underlying diaphragms; and the flat decks must also be properly positioned relative to the pulsation producing diaphragms and these diaphragms must be properly actuated, in order to insure uniform and most effective screening operation.

It is therefore a more specific object of my present invention, to provide an improved diaphragm actuated flat screen assembly, which is simple and durable in construction and highly effective in use.

Another specific object of the invention is to provide improved instrumentalities for mounting and for detachably securing flat screen decks to a support in proper position relative to their co-operating diaphragms, and in a manner whereby the individual screen plates may be quickly and conveniently removed and installed.

A further specific object of this invention is to provide a simplified combination of actuating mechanism and diaphragm and screen plate mountings, whereby the diaphragms will most effectively cooperate with the adjacent screen decks so as to thoroughly and uniformly agitate the fibrous pulp and thus rapidly purge the foreign matter from the good fibres.

Still another specific object of the present invention is to provide an improved diaphragm actuated flat screen all parts of which are readily accessible for inspection, lubrication, and replacement of parts, various elements of which are interchangeably similar and of inexpensive construction, and which may be maintained in most efficient operating condition with minimum loss of time and expense.

These and other specific objects and advan-

2

tages of the invention will be apparent from the following description.

A clear conception of the features constituting my present improvements, and of the mode of 5 constructing and of operating pulsating screens built in accordance with the invention, may be had by referring to the drawings accompanying and forming a part of this specification, wherein like reference characters designate the same or 10 similar parts in the various views.

Fig. 1 is an exploded perspective view of a 15 fragment of my improved diaphragm actuated flat screen assemblage, showing one of the deck frames bearing two of the duplex screen plates, and the cooperating seal strip, lifted from their normal positions in the vat;

Fig. 2 is a transverse vertical section through the assembled pulp screen and diaphragm actuating mechanism;

20 Fig. 3 is a longitudinal central vertical section through an end fragment of the same screen assemblage, showing three diaphragms, actuating mechanisms therefor, and screen deck assemblies cooperating therewith;

25 Fig. 4 is an enlarged central vertical longitudinal section through one of the diaphragm actuating and positioning mechanisms; and

Fig. 5 is a fragmentary section through a corner of one of the screen plates.

30 Referring to the drawings, the improved diaphragm actuated flat screen assemblage shown therein, comprises in general, an elongated open topped vat 6 mounted upon a support 7 and communicating at one side with a flow box 8; a series of horizontal flexible diaphragms 9 forming the bottom of the vat 6 and being separated by transverse rigid partitions 10; a screen supporting frame 11 mounted within the vat 6 above each diaphragm 9; a pair of duplex screen plates

35 12 supported upon each frame 11 and cooperating with adjacent plates 12 to provide a continuous horizontal screen deck above the diaphragms 9; a continuously rotating shaft 13 journaled in bearings 14 mounted upon the vat

40 15 support 7, and having an eccentric portion 15 disposed centrally beneath each diaphragm 9; a connecting rod 16 connecting each eccentric portion 15 with the upwardly adjacent diaphragm 9; and a stabilizer plate 17 associated with each

45 diaphragm 9 laterally adjacent to its actuating rod 16 and eccentric 15.

The main vat 6 and flow box 8 are preferably formed of durable metal such as rust-resistant steel, and the vat and drive mechanism support 50 7 may be of any suitable construction adapted

to permit free inspection of the lower portions of the diaphragms 9 and of the bearings and motion transmitting mechanism. The diaphragms 9 are preferably formed of highly flexible material such as sheet rubber, and have their peripheral edges firmly secured to the side walls of the vat 6 and to the adjacent partitions 10 so as to provide a liquid tight chamber 18 between each diaphragm and the corresponding screen deck plates 12; and the central portion of each diaphragm 9 is clamped between upper and lower reinforcing plates 19, 20 respectively. The transverse partitions 10 are also formed of rust-resistant material, and are firmly secured to the side walls of the vat 6 so as to produce a durable and rigid pulp confining tank. 15

The screen supporting frames 11 are of interchangeably similar and durable construction, and each of these frames 11 consists of a rectangular outer frame having depending integral transverse end flanges 21, and a cross-brace formed integral with the outer frame and also having a depending integral flange 22. The side flanges 21 of the adjoining frames 11 coat with the upper edges of the adjacent vat partitions 10 through inverted U-shaped sealing strips 23 so as to segregate the chambers 18; and the opposite sides of each frame 11 are provided with horizontal flanges 24 adapted to coat with ledges 25 formed within the vat 6 and to be rigidly attached to these ledges 25 by means of studs 26 and nuts 27, see Figs. 1 and 2. Each of the horizontal end flanges 24 of each frame 11 is provided with openings for receiving the studs 26, and with threaded holes 28 for receiving lifting eye-bolts 29, and these eye-bolts serve to effect lifting and lowering of the frames 11 when the nuts 27 have been removed. The frames 11 may be thus firmly secured to the vat 6 during normal use, by means of the studs 26 and nuts 27; but may also be quickly and readily applied or removed with the aid of the threaded holes 28 and eye-bolts 29. 30

The screen deck plates 12 are formed in duplex sets or pairs of suitable material and with rows of slots or perforations, and these plates 12 are also of interchangeably similar construction. Each of the plates 12 has a transverse imperforate central reinforcing strip 30, and is provided at its edges with a series of holes 31 adapted for the reception of flat-head screws 32. These screws 32 are adapted to be screwed into threaded sockets formed in the top of each frame 11, as clearly shown in Fig. 1, and while the plates 12 are carried by and removable with the frames 11, they may also be applied or removed independently of their carrier frames with the aid of the screws 32. The tops of all of the assembled screen plates 12 are smooth and lie in the same horizontal plane, and the screen plates 12 are normally rigidly secured to the frames 11 and are prevented from being distorted by the heavily reinforced supporting frames 11 with their stiffening flanges 21, 22, 24. 45

In order to maintain a smooth upper screening deck and to eliminate corners in which fibres and other solid material might lodge, it is desirable to normally conceal the protruding studs 26 and nuts 27 which hold the frames 11 in place, by means of readily detachable seal strips 33. These seal strips 33 are formed in sections approximately equal in length to the widths of the frames, and each seal strip 33 is attached to the adjacent wall of the vat 6 by means of inclined bolts 34 and has apron plates 35 attached thereto by flat headed screws 36, as illustrated in Figs. 50

1 and 2. The seal strips 33 with the apron plates 35 attached thereto, may be quickly attached to or removed from the vat 6, and when the seal strips 33 are in normal operating position, the apron plates 35 snugly engage the adjacent side flanges 24 of the screen deck supporting frames 11 and thus thoroughly conceal the studs 26 and nuts 27. The downwardly and outwardly inclined disposition of the seal strip attaching bolts 34 co-acting with the oppositely inclined upper inner surfaces of the strips 33, forces the apron plates 35 into snug contact with the frame flanges 24 along the edges of the screen plates 12, thus insuring most effective sealing. 55

While the flexible diaphragms 9 are disposed horizontal and parallel to the screen plates 12, these diaphragms must be distorted or flexed in order to pulsate the liquid through the screen slots or perforations during normal operation of the assemblage, and the flexing movement of the diaphragms 9 should be uniform throughout their areas so as to insure uniform pulsation of the liquid body over the entire screening area and also in order to prolong the life of the diaphragms. The constantly rotating drive shaft 13 with its eccentric portions 15 coaxing with the diaphragms 9 through the connecting bars or rods 16 and plates 19, 20, will effectively flex these diaphragms, but will also tend to tilt the plates 19, 20 thus producing unequal deflection or distortion of the diaphragm sheets; and in order to prevent this undesirable tilting and unequal deflection and to maintain the diaphragms parallel to the plates 12, I have provided a stabilizer or steady plate 17 for each diaphragm 9. The upper ends of the connecting rods 16 are secured to the corresponding lower diaphragm lifter plates 20 by means of bolts 37 and intervening rubber sheets 38, 39 which are spaced apart by slip plates 40, and the lower ends of these rigid rods 16 coat with the adjacent eccentric portions 15 of the shaft 13 through anti-friction or ball bearings 41 confined within eccentric housings 42, see Figs. 2, 3 and 4. The main shaft bearings 14 which are mounted upon the support 7, are also preferably of the anti-friction or ball bearing type, and all of these bearings 14, 41 should be formed to accommodate slight deflections or misalignments between the various driving elements. 50

Each of the stabilizing plates 17 has its upper extremity widened and rigidly attached to the corresponding lower diaphragm lifter plate 20, while its lower narrower end is firmly attached by bolts 43 to the outer oscillating or swinging end of a relatively long horizontal leaf spring 44. The opposite end of each leaf spring 44 is rigidly attached to the main support 7 by means of a bracket 45 and bolts 46, and the plates 17 should be relatively stiff and should also be disposed parallel to the adjacent connecting rods 16. During pulsation or vibration of the diaphragms 9 by the eccentrics and connecting rods, the leaf springs 44 will be vibrated through the stabilizer plates 17, and since the lower ends of these plates are rigidly attached to the vertically oscillating spring ends, and the upper plate ends are likewise rigidly attached to the lower diaphragm actuating plates 20 which are clamped directly to the diaphragms 9, the stabilizers will restrain these diaphragms 9 from tilting out of the horizontal plane which is parallel to the screen plates 12. In this manner, the stabilizing plates 17 insure uniform pulsation of the liquid throughout the entire areas of the screen deck plates 12 and thereby 70

provide for uniform purging of the pulp, and all parts of the actuating and stabilizing mechanisms are freely accessible at all times through the large opposite side openings 47 in the main support 7, see Fig. 2.

During normal operation of the improved screen assemblage, the vat 6 should be supplied with an abundance of liquid pulp covering the screen deck, and the main shaft 13 should be constantly rotated at a suitable speed. The anti-friction bearings 14, 41 should be amply lubricated, and as the shaft 13 rotates it revolves the eccentric portions 15 which coact with the adjacent diaphragms 9 through the connecting rods 16 and plates 19, 20, 38, 39, 40 to rapidly reciprocate or vibrate the flexible diaphragms 9 and to thereby pulsate the body of liquid pulp within the vat 6 through the screen slots or perforations formed in the deck plates 12. During this reciprocation of the diaphragms 9, the stabilizer plates 17 effectively function to prevent undesirable tilting or distortion of the individual diaphragm sheets, and to insure most efficient cooperation of the diaphragms 9 with the adjacent screen plates 12 which are rigidly fixed above the successive pulsating compartments 18 by the ribbed or flanged frames 11. The duplex screen plates 12 while being firmly held in place during normal operation, may be quickly and conveniently removed either in pairs by releasing the seal strips 33 and aprons 35 and thereafter removing the adjacent frames 11, or individually by merely removing the fastening screws 32; and the seal strips 33 and aprons 35 cooperate with the countersunk flat headed screws 32 to provide a flat and unobstructed horizontal screening deck. The seal strips 33 and aprons 35 moreover effectively protect the studs 26 and nuts 27 and prevent foreign matter from lodging or collecting thereon, thus providing a simple but highly effective screening assemblage which may comprise any desired number of individual screen units.

From the foregoing detailed description, it will be apparent that my present invention provides a simple, compact and durable diaphragm actuated flat screen especially adapted to purge liquid pulp or the like, which is highly efficient in operation, and all parts of which are readily accessible for inspection, repair and replacement. The flat screen plates 12 are firmly but detachably maintained in horizontal alignment, and the adjacent diaphragms 9 are effectively stabilized and maintained in proper position relative to the screen plates 12, in a manner which will assure uniform pulsation of the liquid throughout the areas of the successive segregated compartments 18. The driving shaft 13 may also be formed in sections connected by suitable couplings 50 as indicated in Fig. 3, so that any desired number of the improved screening units may be provided dependent upon the screening capacity required, and the partitions 10 and sealing strips 23 coact with the end flanges 21 of the frames 11 to effectively segregate the successive pulsating chambers 18 from each other.

The stabilizer plates 17 cooperate with the eccentric portions 15 and connecting rods 16 to provide simple individual drives adapted to produce smooth but effective actuation of the diaphragms 9 and to maintain these diaphragms substantially parallel to the adjacent screen deck, and the flanged frames 11 firmly retain the screen plates 12 in proper position while still providing for convenient removal thereof. These frames 11 may be quickly removed together with the

screen plates 12 supported thereby, upon removal of the sealing strips 33 and with the aid of the eye-bolts 29; and the individual screen plates 12 may be removed or applied either while the frames 11 remain in normal position, or after removal of these frames from the vat 6. The improved sealing strips 33 and apron plates 35 also coact with the frames 11 and plates 12 to provide a smooth screen deck devoid of projections or obstructions, and provide simple means for protecting the studs 26 and nuts 27, and the entire structure may obviously be manufactured at moderate cost and maintained in efficient operating condition with minimum attention and expense.

15 It should be understood that it is not desired to limit this invention to the exact details of construction or to the precise mode of use, herein shown and described, for various modifications within the scope of the appended claims may 20 occur to persons skilled in the art.

I claim:

1. In a pulsating paper pulp screen, a liquid confining vat having therein a series of segregated compartments, a flexible horizontal diaphragm spanning the bottom of each compartment, each diaphragm having a central rigid reenforcing plate secured thereto, a rigid open frame mounted upon said vat above each compartment, a screen plate mounted upon and spanning each of said frames to provide a continuous horizontal screening deck extending across the tops of all of said compartments, clamping means detachably connecting each screen plate to its supporting frame, other clamping means connecting each of said frames to said vat, sealing strips detachably secured to said vat and concealing said other clamping means, an eccentric revolvable about a horizontal axis centrally beneath each of said diaphragms, a rigid rod connecting each of said eccentrics directly with the corresponding diaphragm reenforcing plate, an approximately horizontal leaf spring disposed closely adjacent to and beneath each of said eccentrics, each spring having one end fixedly secured while its opposite end is freely vertically deflectable, and a rigid stabilizer plate connecting the deflectable end of each leaf spring with the corresponding diaphragm reenforcing plate.

2. In a pulsating paper pulp screen, a liquid confining vat having therein a series of segregated compartments, a flexible horizontal diaphragm spanning the bottom of each compartment, each diaphragm having a central rigid reenforcing plate secured thereto, a rigid open frame mounted upon said vat above each compartment, a screen plate mounted upon and spanning each of said frames to provide a continuous horizontal screening deck extending across the tops of all of said compartments, clamping means detachably connecting each screen plate to its supporting frame, other clamping means connecting each of said frames to said vat, sealing strips detachably secured to said vat and concealing said other clamping means, an eccentric revolvable about a horizontal axis centrally beneath each of said diaphragms, a common horizontal shaft for rotating all of said eccentrics, a rigid rod connecting each of said eccentrics directly with the corresponding diaphragm reenforcing plate, an approximately horizontal leaf spring disposed closely adjacent to each of said eccentrics beneath said shaft, each spring having one end fixedly secured while its opposite end is freely vertically deflectable, and a rigid flat stabilizer

plate connecting the deflectable end of each leaf spring with the corresponding diaphragm reinforcing plate, the upper and lower ends of said stabilizer plates being rigidly attached to the adjacent diaphragms and leaf springs.
